UNITED STATES PATENT OFFICE.

MICHAEL J. ULINE, OF TOLEDO, OHIO.

DEVICE FOR LIFTING ICE CANS.

Application filed January 31, 1927. Serial No. 164,878.

This invention is an apparatus for handling ice cans employed in the manufacture of artificial ice.

In the manufacture of ice sheet metal cans are employed immersed in brine which is cooled by means of pipes arranged in the bottom of the tank or compartment in which the brine is contained and in which a number of the sheet metal cans are arranged, these cans being filled with the water to be frozen.

Heretofore these cans had been lifted out by various types of books or grapples but it frequently happens that in lifting these cans the grapple or hook becomes disconnected from the can. When this happens the can usually drops and very often the freezing coils arranged in the bottom of the tank or chamber are injured to such an extent that the freezing fluid escapes and it is necessary to draw off the brine and likewise the freezing fluid and repair the pipes.

The object of my invention, therefore, is to provide a device for lifting the ice cans, preferably two at a time, which device shall be so constructed that when once it is connected to the top of the can and a pull exerted thereon disengagement will be rendered impossible, thereby completely avoiding the danger of dropping the can and producing the damage heretofore referred to.

With this object in view my invention consists in the novel features of construction and in the manner of combining or arranging the same, all of which will be fully described hereinafter and set forth in the appended claims.

In the drawings forming a part of this specification, Fig. 1 is a view showing the practical application of my invention; Fig. 2 is a vertical sectional view partly in elevation showing one of my improved lifting bars arranged in connection with the top of an ice can; Fig. 3 is a top plan view of the same; Fig. 4 is a side elevation showing the relative positions of the various parts during the lifting operation; and Fig. 5 is a similar view showing the position to which the parts are turned when it is desired to connect or disconnect the lifting bar to the ice can.

Referring to the drawings, 10 indicates a sheet metal ice can which is rectangular in shape and in practice the upper edges of these ice cans are reinforced as indicated at 10^a. In the interest of speed it is desirable

to lift at least two of these cans at one time and consequently I have shown two of these cans shown side by side and in connection with each can I employ a lifting bar 11 and a connecting bar or double tree 12 for engaging and lifting two of these bars at one and the same time, the double tree being raised and lowered by means of a cable 13 hooked to the center thereof. In the reinforced edges of the ice cans there are produced oppositely disposed openings 10^b, these openings being engaged by the reduced ends 14^b of the bolts 14, said bolts being arranged in the sockets 15 produced in the opposite ends of the lifting bar 16. Each bolt is projected outwardly by means of a coil spring 17 and the in-and-out movements of the bolts are limited by means of the cross pins 18 working in the longitudinal slots 19 produced in the bolts, the pins 18 passing transversely through the lifting arms and bolts as most clearly shown in Fig. 2.

In order to connect the lifting bar to the ice can one bolt is inserted in one opening and then the other bolt is retracted sufficiently to permit the introduction of the reduced end into the opening in the reinforced edge of the can. It is only necessary to have one of the bolts retractile and I have only shown one of these bolts of such construction but it will, of course, be understood that if desired both of them can be made retractile. Each lifting bar is formed with an upwardly extending loop 19^a with which engage the hooks 20 arranged at the opposite ends of the double tree 12.

In order to steady the lifting bar while in engagement with the edges of the ice can I provide the laterally or horizontally rearwardly extending arms 21 at each end of the lifting bar and these horizontal arms are each provided with a curved finger or hook 22 which is brought into engagement with the edges of the can when an upward pull is exerted upon the lifting bar, the loop 19 being so positioned with reference to the pivotal points of the bolts that these fingers or hooks 22 will remain in engagement with the upper edges of the ice can so long as an upward pull is exerted upon the loop. This prevents the bolts becoming disconnected from the can and consequently avoids the possibility of dislocation and damages incidental thereto.

The lifting position is most clearly illustrated in Figs. 1, 2, 3 and 4 and in Fig. 5

I have shown the positions which the parts are made to assume when the device is being disconnected from the can, the loop 19 being drawn down to a horizontal position and 5 consequently the arms 21 are tilted upwardly lifting the fingers or hooks 22 away from the edge of the can and the bolt can then be withdrawn from engagement with the opening at the edge of the can and the lifting bar removed or detached from the can.

The device herein shown can be quickly and easily attached to and detached from the ice cans and when in operation lifts the cans directly upwardly and all danger of 15 disconnection is entirely avoided.

Having thus described my invention, what I claim is:—

1. In a device of the kind described, a lifting bar provided with bolts at each end for 20 engaging the sides of an ice can, and arms rigid with said bar and adapted to engage the edges of the ice can at points spaced from the engagement of the bolts with the sides of the can.
- 25 2. In a device of the kind described, a lifting bar having bolts at their opposite ends for engagement with the opposite sides of an ice can, and arms rigid with the lifting bar and having hooks at their ends for engagement with the edges of the can at points spaced from the engagement of the bolts with the sides of the can.
- 30 3. In a device of the kind described, a lifting bar having means at its ends for engaging an ice can at oppositely disposed points, said lifting bar being also provided at its ends with means for engaging the edges of the ice can at points spaced from the engagement of the bar ends with the can and 40 whereby disengagement of the bar from the can is prevented.

4. In a device of the kind described, a lifting bar having means at its ends for engaging the sides of an ice can at oppositely disposed points, said bar having a loop by 45 means of which said bar is lifted, said bar also being provided with means at its opposite ends for engaging the edges of the ice can at points spaced from the bar ends, said edge engaging means being so arranged 50 with reference to the lifting loop that said means are brought into engagement with the edges of the can when a lifting strain is placed upon the loop.

5. In a device of the kind described, a lifting bar provided with bolts at its opposite ends, one of said bolts being retractile, a lifting loop and laterally extending arms each provided with hooks at its ends, said hooks 60 being spaced from the bolts carried at the ends of the lifting bar:

6. In a device of the kind described, a lifting bar having bolts at its opposite ends, one of said bolts being spring actuated, an upwardly extending loop, and horizontally extending arms, each arm terminating in a hook at its end, said hooks being adapted to engage the edges of an ice can at points spaced from the engagement of the bolts with said can.

7. In a device of the kind described, a lifting bar having bolts at its opposite ends, a lifting loop and steadyng arms provided with hooks at their ends, the lifting loop and arms being arranged at an angle to one another and whereby when an upward pull is exerted upon the loop the arms will be maintained in a horizontal position.

In testimony whereof, I hereunto affix my signature.

MICHAEL J. ULINE.
